SCRIBING TRAMMEL FOR STRAIGHT AND CURVED LINES

Paul Manthey, Bronx, N. Y.

Application May 6, 1939, Serial No. 272,086

1 Claim. (Cl. 33—42)

This invention relates to a marking implement, particularly one having longitudinal means of adjustment, which by easy manual manipulation, parallel lines or circles may be drawn or scribed accurately upon the flat surfaces of an object.

One of the objects of the invention is to provide a bar of indefinite length with standard graduations on one of its sides and accurately spaced indentations on the adjacent top side, and a point carrying head slideable on the bar.

Another object is the provision of means whereby a slideable head, having a locking pin engageable in the spaced indentations of the bar, may be quickly and accurately moved throughout the length of the bar.

These and other advantageous objects are attained by the novel construction and arrangement of parts hereinafter described and shown in the accompanying drawing, constituting a material component of this disclosure, and in which:

Figure 1 is a side elevational view of an embodiment of the invention, partially in section, showing details of construction.

Figure 2 is a top plan view of the same.

Figure 3 is a fragmentary sectional view taken on line 3—3 of Figure 1.

Figure 4 is a cross sectional view of the graduated bar showing the spaced indentations therein.

Referring to the drawing in greater detail, the numeral 10 designates a rectangular bar having engraved on its front face graduations 11 representing inches, each subdivided into sixteen equal parts.

It will be seen that these graduations, beginning at zero do not start from the extreme left hand end of the bar, a space being left blank, for reasons that will become apparent as the description continues.

As shown this bar is graduated a distance of 24" from zero, but may be of greater or less length as desired; at the right of the last graduation, is a blank space.

On the upper, adjacent side of the bar 10 are provided a longitudinal row of conical indentations 12, accurately spaced and in line with each graduation on the bar 10.

At the left hand end of the bar is a transverse annular opening adapted to adjustably receive a scriber 13, vertically slideable therein, and a clamp screw 14 in its end for holding the scriber in adjusted position; for convenience in making

adjustment, a knurled knob 15 is fixed on the scriber.

Slidable on the bar is a head 16, having a rectangular opening longitudinally therethrough, the head comprising a substantially elongated rectangular block of metal, reduced in width at one end, as at 17, the wide portion having concaved sides 18 forming finger grips to facilitate it moving along the bar.

In the reduced portion 17 of the head is an opening forming a bearing for a detent locking pin 19, having a pointed end 20 adapted for engagement with indentation 12 formed in the graduated bar 10; concentric with the pin bearing is a spring casing 21 threadably secured in 15 the head element 17. The locking pin 19 extends upwardly through a disc 22 engaged in the upper interior portion of the spring casing 21, providing a guide bearing for the locking pin.

To hold the head 16 in adjusted position, the locking pin 19 is held in downward position by a spring 23, acting between the disc 22 and a collar 24 fixed on the pin.

When it is desired to change the setting of the head, the locking pin 19 must be raised 25 from engagement with the indentations 12 of the bar 10. This is accomplished by depressing a lever 25, pivoted in a slotted stud 26, secured in the head near the spring casing 21.

The lever 25 has at one end a forked element 30 27, adapted to receive the locking pin 19 and engage the locking pin head 28 when raised by the downward movement of the lever handle 29.

Aligned with the locking pin 19 is a cylindrical roll 30, rotatably held by a shouldered screw 31, 35 threadably engaged on the under side of the slideable head 16.

Near the right hand end of the head, are screw threaded openings 32 and 33, in vertical alignment, the upper opening 32 being receptive of 40 a threaded rod 34 having near its upper end a groove adapted to receive a pin 35, fixed in the hub of a revolvable handle knob 36.

In the lower opening 33 of the block is removably secured a pointed scriber 37 in registration 45 with the rod 34.

Cut through the front wall of the block 17 is a bevelled recess 38, best shown in Figure 3, its inner edge being adjacent the graduated face of the bar 10 and terminates in a knife-like edge 50 which, when the locking pin 20 is seated in any of the indentations 12 of the bar 10, provides a reading line coincident with and parallel to the graduations on the bar.

It will be understood that the slide head 16 may 55

be moved to the left, as shown by dotted outline in Figure 1, or extended to the right when it is desired to use the extreme graduated length of the bar.

5 When it is desired to scribe a line parallel to an edge, at a distance of 3" from the edge as an example, the head 16 is moved into a position where the indicating line 38 of the slide 16 coincides with the 3" mark on the graduated bar; the head will be automatically locked in position 10 when the locking lever 25 is released.

In use, the roll 30 is held in contact with the edge of the work and the instrument moved in a direction parallel to the edge. The scribe 13 15 may be raised or lowered, if necessary, to keep the device in a substantially level position.

When it is desired to scribe circles, and it is known that the distance between the axis of the scribe 13 and the reading line 38 of the head 16, 20 is 3" and the distance from the reading line 38 to center of scribe 37 is 2", then the center distance between the scribes 13 and 37 is 5".

If it is required to scribe a circle 10" in diameter, divide 10" by 2, obtaining 5" as the radius 25 of a 10" circle; from this radius is subtracted the distance between the reading line 38 and the

scriber point 37, which is 2", and obtain a dimension of 3" which is the correct setting of the head as shown in Figure 1.

Although the foregoing is descriptive of the best known embodiment of the invention, minor 5 changes may be made within the concept of the claim hereto appended.

Having thus described the invention, what is claimed as new, and is desired to secure by Letters Patent, is:

A marking implement comprising a bar of square cross section throughout its entire length, said bar bearing graduations on one side and having a central row of sharply defined conical indentations in a side adjacent the graduations 15 and spaced apart in conformity therewith, a scribe adjustably engaged in one end of said bar, a head slidable on said bar, a spring pressed pin in said head having a point selectively engageable in said indentations, lever means to retract 20 said pin, and a single roller journaled on the opposite side of said head from said pin and in axial register therewith, said head having a bevelled lateral recess through which said graduation may be observed. 25

PAUL MANTHEY.
